UNITED STATES PATENT OFFICE.

SHERMAN H. GUTHRIE, OF YORK TOWNSHIP, STAFFORD COUNTY, KANSAS.

WINDMILL AND PUMP COUPLING.

SPECIFICATION forming part of Letters Patent No. 783,632, dated February 28, 1905.

Application filed April 21, 1904. Serial No. 204,277.

To all whom it may concern:

Be it known that I, SHERMAN H. GUTHRIE, a citizen of the United States, residing in York township, in the county of Stafford and State 5 of Kansas, have invented new and useful Improvements in Windmill and Pump Couplings, of which the following is a specification.

My invention relates to pump connections, and particularly to connections between the 10 reciprocating rod of a wind-wheel and the pump-rod and lever or handle of a manual lever-pump.

The object of my invention is to provide a connection that will be automatic in action, 15 thereby obviating the use of bolts, wrenches, &c., which is necessary in applying the connections most generally used.

Furthermore, the object of the invention is to produce a coupling that can be operated 20 automatically by either the reciprocating rod of a wind-wheel when it is desired to operate the pump by wind-power or when the reverse action is desired and the operator wishes to connect the pump-handle with the pump-rod 25 the manipulation of the pump-handle will throw the pump-rod out of engagement with the reciprocating rod of the wind-wheel and at the same time form a connection between the pump-handle and pump-rod.

Finally, the object of the invention is to produce a connection that is comparatively simple 30 in construction, strong, and efficient for the purpose for which it is designed.

It is usually desirable to employ pumps in 35 connection with wind-wheels, and in case the wind is not sufficient to drive the wheel and it becomes necessary to operate the pump by means of a manual lever or handle the reciprocating rod of the pump must be disengaged 40 from the reciprocating rod of the wind-wheel and connected with the pump-handle. In making the change from one power to the other it has generally been the practice to use separate and distinct means, and it frequently happens 45 that both the reciprocating rod of the wind-wheel and the pump-handle are left connected at the same time. This is obviated by my in-

vention, as the construction is such that either one (the reciprocating rod of the wind-wheel or the pump-handle) must be disconnected, it 50 being impossible by the construction of my invention to have both connected at one and the same time. Should the operator inadvertently leave the pump-handle connected with the pump-rod and the wind-wheel should be 55 started before the disengagement of the handle, the accidental breakage of any of the parts are thus avoided.

In describing my invention in detail reference will be had to the accompanying drawings, 60 forming part of this specification, and in which like numbers denote corresponding parts in the several views, and in which—

Figure 1 is a perspective view of my invention. Fig. 2 is a cross-section of the cylinder. 65 Fig. 3 is a sectional view of the split collar attached to the reciprocating rod of the wind-wheel.

In the drawings, 1 denotes a pump of any ordinary construction having a cylindrical 70 top, over which a ring 2 is seated. The ring 2 has secured thereon two vertical extending arms 3 and 3', which diverge in the center, but contact at each end, the opposite ends of the vertical arms being secured to a divided collar 75 4, said divided collar having a central aperture in the periphery, of which 1 form two spiral grooves 5 and 5'. A cylinder 6, provided with an approximately rectangular shaped aperture extending longitudinally thereof and 80 provided with spiral threads 7 and 7' on its outer surface, is supported by the divided collar 4, and the spiral thread is held in engagement with the spiral grooves carried by the collar. The cylinder is also provided with extensions 8 and 8' on each end, thereby preventing the accidental disengagement of the cylinder with the divided collar. 85

On the pump-rod 9, which has a flattened portion at one end, two pins 10 and 10' are secured, said pins extending outward from one side and being oppositely disposed from each other. 90

The pump-handle 11 is carried by a link

12, said link having one end pivoted between the vertical arms and its opposite end pivoted to the pump-handle. At one end of the handle two diverging arms 13 and 13' are 5 formed integral with the handle, and to the ends of the diverging arms a collar 14, having a hook-shaped projection 15 formed integral therewith, is pivoted, said collar carrying a ring 14', having flanges on each end and 10 adapted to rotate in the collar 14, through which the pump-rod reciprocates when the pump is operated by means of the wind-wheel. The collar 14 is made large enough to permit 15 of a lost motion sufficient to allow the hook-shaped projection to come in engagement with the pin 10.

Upon the end of the reciprocating rod of the wind-wheel is a collar 16, having an extension 17 with a slanting edge, by which the 20 collar is secured to the reciprocating rod of the wind-wheel by means of bolts or rivets. The collar 16 is provided with a slot 18, extending vertically the length of the collar, and this vertical slot has a cut-away portion 19, 25 which is adapted to engage the pin 10', carried by the pump-rod, when it is desired to operate the pump by means of the wind-wheel. A split ring 20, having an extension at each end, is carried by the collar 16. The slot 21 30 of the split ring 20 is adapted to register with the slot 18 of the collar 16.

The operation of my device is as follows: The device is secured upon the top of a pump by means of the ring, and the pump-rod reciprocates when disconnected from the pump-handle through the collar 14, and when disengaged from the reciprocating rod of the wind-wheel the pump-rod reciprocates through the split collar carried by the ring 20. 35 It will be observed that by raising or lowering the cylinder a partial rotation is caused by the spiral threads carried by the cylinder. When the operator desires to connect the pump-handle to the pump-rod, the handle is 40 pressed downwardly along the pump. By this action the collar 14 is forced up against the cylinder, and the cylinder is forced upward and at the same time is partially rotated. By the partial rotation of the cylinder the pump-rod is turned far enough to disconnect pin 10' 45 from the slot 19. The handle is then lifted, and the hook-shaped projection of the collar 14 is brought in engagement with the pin, and the pump can then be operated by the pump-handle. The handle being thus connected to the 50 pump-rod and the wind-wheel being started, the collar 16, carried by the reciprocating rod, is forced down on the cylinder, and as the cylinder is forced down the same is partially 55 rotated, and the partial rotation of the cylinder causes the pump-rod to partially rotate, and the pin is disengaged from the hook-shaped projection carried by the collar. As 60

soon as the pin 10 is disengaged from the hook-shaped projection the weight of the 65 pump-rod will cause the same to descend until the pin 10 rests on the top of the ring by which the device is secured to a pump. The hook-shaped projection and slot 19 being opposite to each other, it will be observed that 70 when one is released the other is in a position to be engaged. The downward motion of the collar 16 presses the cylinder downward in order to release the pin 10 from engagement with the hook-shaped projection, and 75 when the pump-rod descends of its own weight or when the wind-wheel rod rises the pin 10' rides down over the slanting edge of the collar, thereby twisting the wind-wheel rod, and as the pin 10' slides into alignment with 80 the slot 19 the spring of the rod, caused by the twisting, will cause the pin 10' to be forced into the slot 19, and the pump will then be connected for operation by the wind-wheel.

Having fully described my invention and 85 the operation of the same, I desire to be understood that while I have described a simple and preferred form of my invention I do not limit myself to the structural details herein set forth, but reserve the right to any changes, 90 modifications, and alterations within the spirit and scope of my invention and which may be resorted to without sacrificing the utility of the same.

Having fully described my invention, what 95 I claim as new, and desire to secure by Letters Patent, is—

1. The combination with a pump-handle of a pump-rod and a wind-wheel reciprocating rod 100 a ring seated on the pump and vertical arms carried by the ring, a cylinder supported by the arms, means for giving a partial rotary motion to the cylinder, a collar having a hook-shaped projection pivoted to the pump-handle and means for connecting the pump-rod and pump-rod and the pump-rod and wind-wheel reciprocating rod and means for supporting the handle as and for the purpose 105 set forth.

2. In a device of the character described, a 110 collar supporting vertical diverging arms, a divided collar carried by the vertical diverging arms, a cylinder carried by the divided collar and means on the cylinder for partially rotating the same, a collar having a vertical 115 slot and an extension carried by the reciprocating rod of the wind-wheel and means carried by the pump-rod for connecting the pump-handle and the reciprocating rod of the wind-wheel and vice versa as and for the purpose 120 described.

3. In a device of the character described, a 125 ring supporting vertical diverging arms, a divided collar supported by the vertical arms, a cylinder provided with spiral thread on its outer surface supported by the divided collar,

a pump-handle having diverging arms pivoted to a link-support, said diverging arms pivoted to a collar provided with a hook-shaped projection, pins secured to the pump-rod and adapted to engage the hook-shaped projection carried by the collar as and for the purpose set forth.

In witness whereof I have subscribed my name in the presence of two subscribing witnesses.

SHERMAN H. GUTHRIE.
